UNITED STATES PATENT OFFICE.

HENRY P. KRAFT, OF RIDGEWOOD, NEW JERSEY.

STOPPER FOR WATER-BOTTLES OR THE LIKE.

1,301,711.

Specification of Letters Patent. Patented Apr. 22, 1919.

Application filed November 1, 1915. Serial No. 58,967.

To all whom it may concern:

Be it known that I, HENRY P. KRAFT, a citizen of the United States of America, residing in Ridgewood, in the county of Bergen and State of New Jersey, have invented certain new and useful Improvements in Stoppers for Water-Bottles or the like, of which the following is a specification.

This invention relates to stoppers for water bottles or similar devices, and aims to provide certain improvements therein.

The invention is particularly directed to stoppers for water bottles which have a large neck, and hence require a socket piece which is of considerably larger dimensions than the ordinary screw stopper. Such socket pieces or so-called "necks" are usually made of oval form and are constructed of sheet metal. Each neck carries a female part formed with screw threads into which the stopper screws. The object of the present invention is to provide an extremely cheap and simple construction of this character.

In the drawings, wherein I have illustrated one form of the present invention,

Figure 1 is a vertical longitudinal section of the device.

Fig. 2 is a transverse section.

Fig. 3 is a top perspective view.

Referring to the drawings, let A indicate the device as a whole which as shown comprises two parts, the neck proper B and the female screw-threaded portion C. The neck proper B is formed with a bottom wall *a* and side walls *b*, which walls are formed integrally by cupping a sheet metal plate. Preferably the side walls are concave so as to provide a better and more secure hold for the rubber walls of the water bottle.

The screw-threaded member C is also formed of sheet metal and is provided with screw-threaded walls *c* and a lower flange *d*. The threaded member and neck member are united at the bottom of the screw-threaded member, the neck member being formed with a suitable aperture *e* through which the liquid is poured to fill or empty the bottle.

According to the preferred form of my invention this connection is made by a flange *f* formed on the neck member and turned over the flange *d* formed on the screw-threaded member. When this construction is followed the neck member is perforated at *e* in such manner as to form a smaller hole than that eventually required, and the flange *f* is then forced upwardly whereby the hole

is enlarged. The screw-threaded member is then fitted over the upturned flange *f* and a subsequent operation turns or swages the flange *f* down over the flange *d*. Together 60 they form a seat for the usual type of stopper which has a packing washer carried at the bottom of the stopper. If desired, however, a flange *g* may be provided at the top of the screw-threaded member which forms 65 a seat for that type of stopper which carries a packing gasket at its upper part.

It will be observed that the structure thus formed is open at its top, and it may occur that in filling the bag the space between the 70 screw-threaded member and the neck member may be filled or partially filled with liquid. To avoid the subsequent spilling of this liquid when the bag is in use, I provide means for draining such liquid into 75 the bag itself. Such means preferably comprise a hole or holes *h* made in the screw-threaded member close to the seat. These holes permit the free drainage of any water contained in the neck member back into the 80 bottle.

While I have shown and described one construction of the invention, it will be understood that I do not wish to be limited thereto, since various changes can be made 85 therein without departing from the spirit of the invention.

What I claim is:—

1. In a device of the character described, the combination of an open-topped neck 90 member provided with an aperture in its bottom, and a screw-threaded socket member connected to said neck member at its aperture, and supported solely by such connection.

2. In a device of the character described, the combination of an open-topped neck member provided with an aperture in its bottom, and a screw-threaded socket member connected to said neck member at its aperture, 100 said members having interlocking flanges for connecting the parts, and said connection forming the sole support for the socket member.

3. In a device of the character described, 105 the combination of an open-topped neck member provided with an aperture in its bottom, a screw-threaded socket member connected to said neck member at its aperture, and means for draining any liquid from the 110 neck member into the bottle.

4. In a device of the character described,

the combination of an open-topped neck member provided with an aperture in its bottom, a screw-threaded socket member connected to said neck member at its aperture, and means for draining any liquid from the neck member into the bottle, said means comprising holes formed in the screw-threaded member.

5. In a device of the character described, 10 the combination of an open-topped neck member constructed in one piece, and provided with an aperture in its bottom and a screw-threaded socket member of larger diameter than said aperture, said socket

member being provided with an inturned 15 flange, and said neck member being formed with a flange turned over upon said first-named flange, whereby to connect the parts and to form a seat for the stopper, said socket member being supported solely by 20 such connection.

In witness whereof, I have hereunto signed my name in the presence of two subscribing witnesses.

HENRY P. KRAFT.
